ATTORNEY.

UNITED STATES PATENT OFFICE.

HERMAN L. GREVE, OF NEW YORK, N. Y., ASSIGNOR TO INTERNATIONAL MAILING TUBE AND WRAPPER COMPANY, A CORPORATION OF NEW YORK.

MAILING-WRAPPER.

1,376,872.

Specification of Letters Patent.

Patented May 3, 1921.

Application filed July 9, 1919. Serial No. 309,744.

To all whom it may concern:

Be it known that I, HERMAN L. GREVE, citizen of the United States, and resident of the city of New York, in the county of 5 Kings and State of New York, have invented certain new and useful Improvements in Mailing-Wrappers, of which the following is a specification.

My invention relates to mailing wrappers 10 and particularly to that class relating to the mailing of books and packages of similar shape.

The object of my invention is to provide a wrapper that is sufficiently stiff and strong 15 to thoroughly protect the article wrapped from being injured in passing through the mail and further, a construction, the parts of which can be stamped from a sheet of flexible paper or other suitable material 20 and all connected together ready to wrap a package but which can be delivered to the user in bundles containing the wrappers in flat or knock-down form.

A further object is to provide a wrapper 25 in which the two body portions are held together in relatively adjustable relation by means that may be readily disconnected to permit replacement of either body portion that may be damaged by a new part.

30 A further object is to provide means for protecting the ends of the book or other package, as well as the sides and end portions thereof and to hold said end protecting portions to the body portion in such 35 manner as to permit it to pivot or turn relative to the body portion to which it is attached.

Referring to the drawings which form a part of this specification;

40 Figure 1 is a plan view of the inner side of one body portion of my improved wrapper.

Fig. 2 is an end view of the construction shown in Fig. 1.

45 Fig. 3 is a plan view of the inner side of the other body portion with the strip having the end flaps attached thereto.

Fig. 4 is an end view of the construction shown in Fig. 3.

50 Fig. 5 is a plan view of the inner side of the wrapper showing the parts assembled ready for the user.

Fig. 6 is an end view of the assembled parts as illustrated in Fig. 5.

Fig. 7 is a perspective view of a wrapper 55 with a book therein, which illustrates the wrapper as it appears when the body portions are covered to permit the portions to bend easily and conform to the shape of the book in the act of wrapping the same. 60

Fig. 8 is a view of the opposite side of the wrapper with the book inclosed and disclosing the means for fastening the wrapper in position on the book.

Fig. 9 is a perspective view of the wrap- 65 per as it appears when the body portion is not scored; and

Fig. 10 the opposite side to that disclosed in Fig. 9 with the book fully inclosed and package fastened ready for mailing. 70

A, indicates one body portion, A' the scoring and A² the outer edge portions of the wrapper, and B the other body portion to which is attached the strip C which is held thereto by the fastening means D comprising a loosely fitting rivet which permits the strip C to turn relative to the body portions A and B to the position indicated by the dotted lines E. In the portion B are two parallel slots F—F respectively 80 through which the interlocking ends G—G respectively are passed and locked together as shown at H, thus forming a band which slidingly engages the guide I and thus holds the body portions A and B together in adjustable relation. The edges A² are turned 85 to form a bead to stiffen the edge and thus prevent the edge portion from being easily torn and at the same time move perfectly to protect the ends of the book when 90 wrapped, since they extend beyond the end of the book when the wrapper is in position as illustrated in Figs. 7 and 8.

The book is wrapped as illustrated in Figs. 7 and 8, the free ends of the strip C 95 being folded over the ends of the book as shown after the body portions have been adjusted to the length of the book J. The button K is fastened to the outer side of the portion A and the cord attached thereto 100 is passed around the wrapper as shown and fastened to the button in the usual manner thus holding all the parts securely together. It is obvious that the interlocked ends G—G 105 may be easily disengaged to permit the body portions to be entirely separated if found desirable. The strip C is preferably made the same in length as that of the body por-

tions and can be blanked at the same time and from the same stock as that of the body portions A and B, thus saving time in making the wrapper.

Having thus described my invention, I claim as new and desire to secure by Letters Patent:-

1. A wrapper made of flexible material comprising two longitudinally extending portions having means for holding them together in relatively adjustable relation, and a strip portion held to one of said body portions, in adjustable relation thereto, the ends of which are adapted to overlie the ends of a package held within the wrapper.

2. A wrapper made of flexible material comprising two longitudinally extending portions having means for holding them together in relatively adjustable relation, and a strip portion held to one of said body portions, in pivotal relation thereto, the

ends of which are adapted to overlie the ends of a package held within the wrapper.

3. A wrapper made of flexible material, comprising two longitudinally extending portions one of which is provided with two parallel slots extending therethrough and the other of which is provided with interlocking end portions which extend through said slots and are adapted to slide therein; and a strip portion held to one of said body portions, in adjustable relation thereto, the ends of which are adapted to overlie the ends of a package held within the wrapper.

Signed at New York city, in the county of Kings and State of New York this 8th day of July, A. D. 1919.

HERMAN L. GREVE.
